HYDROMETRIC TESTER

Emil A. Stromberg, Chicago, Ill.

Application September 14, 1939, Serial No. 294,793

14 Claims.

(Cl. 265—46)

The present invention relates to testers of the hydrometric type and particularly those having thermometric means in connection therewith, the invention pertaining to the latter.

An object of the invention is the provision in a tester having the usual jar, suction tip, suction bulb, and hydrometric float, a novel thermometric device which comprises a plug of resilient material, fitting in the jar with a sealing contact and having a passage for the liquid to pass from one side to the other of the plug, together with a chamber in the plug connected to the passage and in which the bulb of the thermometer carried by the plug is located to register the temperature of the liquid passing into and through such chamber. Incidentally, by locating the thermometer bulb within the resilient plug it is protected from all danger of damage.

The invention also comprehends novel means for the protection of the bend of the thermometer which is located without the plug although the legs of the U-shaped thermometer are within the plug.

Other objects, advantages, capabilities, features, and the like are comprehended by the invention as will later appear and as are inherently possessed by the invention.

Referring to the drawing:

Fig. 1 is a view in elevation of a tester in which the invention is embodied;

Fig. 2 is a fragmentary sectional view of the device, on an enlarged scale, showing the invention applied to the tester;

Figs. 3, 4, and 5 are transverse sectional views taken in planes represented by lines 3—3, 4—4, and 5—5 in Fig. 2 of the drawing;

Fig. 6 is a view similar to that shown in Fig. 2 but of an alternative form;

Fig. 7 is a transverse sectional view taken in a plane represented by line 7—7 of Fig. 6;

Fig. 8 is a view similar to that shown in Fig. 2 but of a further alternative form; and,

Fig. 9 is a transverse sectional view taken in a plane represented by line 9—9 in Fig. 8 of the drawing.

Referring more in detail to the drawing, the embodiments selected to illustrate the invention are shown in connection with a hydrometric type of tester comprising a jar 1 which may be of hollow glass or the like, a suction tip 2 suitably connected to the lower end of the jar and having a suction tube 3, a suction bulb 4 connected to the upper end of the jar, and a hydrometric float 5 within the jar.

Within the jar as at the lower portion thereof,

or at any intermediate portion, is located a thermometric device 6 constituting the novel invention herein disclosed. This device comprises an elongated plug 7 which may be of rubber, or other resilient or like material. This plug has end portions 8 and 9 of such size as to fit with a liquid sealing contact with the inner surface of the jar, and an intermediate body portion of smaller size so as to provide a circumambient channel 10 which forms a closed chamber between the end portions 8 and 9 and within the jar wall which encompasses the plug, wherein is located a data bearing interpolation chart 11. This chart is preferably of such material, such as Celluloid or the like, which will retain a curved shape and also clasp the body portion of the plug, as shown.

Through the plug extends a passage 12 for establishing communication between the lower and upper chambers 13 and 14 of the jar at both sides or ends of the plug. Also within the plug is provided a chamber 15 which may have spaced passages 16 and 17 connected to the passage 12 so that when the liquid is drawn up in the passage 12 it will also pass or bypass into and through the chamber 15 by way of passages 16 and 17, or which may have a passage 15a with or without the passage 17, the liquid passing through the passage 15a when the liquid is drawn up in the jar 1.

The plug carries a thermometer which is preferably of U-shape and comprises a graduated long leg 18 extending through an aperture 19 provided in the end portion 9 of the plug and located in a groove 20 provided in the side of the body portion of the plug so that the scale bearing face 21 of the thermometer will be disposed in the chamber 10 and between the edges of the curved chart 11, a short bulb leg 22 extending through an aperture 23 and having at its end a bulb 24 located within the chamber 15, and a bend 25 located outside the end portion 9. The end portion 9 may have a flange portion 26 as shown. Because the plug 7 is composed of resilient material, it is facile to insert the thermometer in place as by pushing the leg 18 through the hole 19 and the bulb 24 and leg 22 through the hole 23, the bend 25 remaining outside, and the resilient material around the holes 19 and 23 being in resilient sealing contact with the legs 18 and 22.

In Fig. 2 the plug is shown in place with the thermometer connected at the lower end thereof, but in Figs. 6 and 8 the plug is shown in reverse position with the thermometer connected at the upper end thereof. In that case the float 5, if no means were provided to prevent it, would contact

the bend 25 and either the bend or the float or both might be damaged. To avoid that the flange 26 may have upwardly and inwardly extending projections 27 of the same material as the plug or even of stiffer material to act as a guard to ward off any contact with the bend 25 by the base of the float 5, as shown in Figs. 6 and 7. On the other hand, as shown in Figs. 8 and 9, the end portion 9 may have an extension 28, the upper end of which is well above the bend 25 and has an elongated recess 29 in which the bend 25 is located. The bottom of the float 5 may only contact the top of the extension 28 and not contact the bend 25.

In use, after the suction bulb 4 has been squeezed and then permitted to expand, the liquid to be tested is drawn up by way of the tube 3 and tip 2 into the chamber 13 and thence by way of the passage 12 into the float chamber 14. The specific gravity of the liquid will be indicated on the stem of the float 5. At the same time the liquid will also flow through the chamber 15 by way of passages 16 and 17 or by way of passages 16 and 15a, or both 16 and 17 and the passage 15a, as the case may be, so that the thermometer bulb 25 contacted by the liquid will transmit to the temperature responsive substance of the thermometer heat which will be indicated as temperature on the scale 21. The temperature and specific gravity indication may then be interpolated by the data on the chart 11 to give the desired information about the state of the liquid as usual in the use of a hydrometric-thermometric tester of the type described. It will thus be seen that the chamber 15 is in communication with the chambers 13 and 14 at both sides or ends of the plug by way of the passages 16, 17 and 12, or by way of 12, 16 and 15a, or 15a, 16 and 12.

While I have herein described and upon the drawing shown a few illustrated embodiments of the invention, it is to be understood that the invention is not limited thereto but comprehends other constructions, details, arrangements of parts, features, and the like, without departing from the spirit of the invention.

Having thus disclosed the invention,

I claim:

1. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug; a chamber provided in said plug and having spaced passages connected to said communication passage in said plug, and a thermometer carried by said plug and having its bulb located in said chamber in said plug.

2. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug; a chamber provided in said plug and having spaced passages connected to said communication passage in said plug, and a thermometer carried by said plug and having its bulb located in said chamber in

said plug, said plug having a circumambient channel to provide a sealed space encompassing said plug and within the surrounding wall of the jar, and a data bearing interpolation chart in said channel, said thermometer having its graduated portion in said channel adjacent said chart.

3. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug; a chamber provided in said plug and having spaced passages so located as to have communication with the chambers at both sides of the plug, and a thermometer carried by said plug and having its bulb located in said chamber in said plug, said plug having a circumambient channel to provide a sealed space encompassing said plug and within the surrounding wall of the jar, and a data bearing interpolation chart in said channel, said thermometer having its graduated portion in said channel adjacent said chart, said thermometer being of U-shape with the bulb leg thereof extending through an end portion of the plug and into said chamber in said plug, and with the graduated leg thereof extending through said end portion of the plug and into said channel.

4. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug; a chamber provided in said plug and having spaced passages connected to said communication passage in said plug, and a thermometer carried by said plug and having its bulb located in said chamber in said plug, said plug having a circumambient channel to provide a sealed space encompassing said plug and within the surrounding wall of the jar, and a data bearing interpolation chart in said channel, said thermometer having its graduated portion in said channel adjacent said chart, said thermometer being of U-shape with the bulb leg thereof extending through an end portion of the plug and into said chamber in said plug, and with the graduated leg thereof extending through said end portion of the plug and into said channel, the bend of the thermometer extending outwardly of said end portion of the plug, and said end portion of the plug having a projecting portion for preventing contact with said bend by the float.

5. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug; a chamber provided in said plug and having spaced passages connected to said communication passage in said plug, and a thermometer carried by said plug and having its bulb located in said chamber in

said plug, said plug having a circumambient channel to provide a sealed space encompassing said plug and within the surrounding wall of the jar, and a data bearing interpolation chart in said channel, said thermometer having its graduated portion in said channel adjacent said chart, said thermometer being of U-shape with the bulb leg thereof extending through an end portion of the plug and into said chamber in said plug, and with the graduated leg thereof extending through said end portion of the plug and into said channel, the bend of the thermometer extending outwardly of said end portion of the plug, and said end portion of the plug having an extension with a recess therein, and said bend being located within said recess where contact with the bend by the float is prevented.

6. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, a chamber provided in said plug and having passages which communicate with the chambers at both sides of the plug, and a thermometer carried by the plug and having its bulb located in the chamber in the plug.

7. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, a chamber provided in said plug and having a passage connected to said communication passage in said plug and a second passage connected to one of the chambers at both sides of the plug, and a thermometer carried by the plug and having its bulb located in the chamber in the plug.

8. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, a chamber provided in said plug and having passages so located as to have communication with the chambers at both sides of the plug, and a thermometer carried by said plug and having its bulb located in said chamber in said plug, said plug having a groove in a side of the body of the plug between the end portions of the plug, said thermometer having its graduated portion in said groove, said thermometer being of U-shape with the bulb leg thereof extending through an end portion of the plug and into said chamber in said plug, and with the graduated leg thereof extending through said end portion of the plug and into said groove.

9. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the

jar at both sides of the plug, a chamber provided in said plug and having passages so located as to have communication with the chambers at both sides of the plug, and a thermometer carried by said plug and having its bulb located in said chamber in said plug, said plug having a groove in a side of the body of the plug between the end portions of the plug, said thermometer having its graduated portion in said groove, said thermometer being of U-shape with the bulb leg thereof extending through an end portion of the plug and into said chamber in said plug, and with the graduated leg thereof extending through said end portion of the plug and into said groove, the bend of the thermometer extending outwardly of said end portion of the plug, and said end portion of the plug having a projecting portion for preventing contact with said bend by the float.

10. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, a chamber provided in said plug and having passages so located as to have communication with the chambers at both sides of the plug, and a thermometer carried by said plug and having its bulb located in said chamber in said plug, said plug having a groove in a side of the body of the plug between the end portions of the plug, said thermometer having its graduated portion in said groove, said thermometer being of U-shape with the bulb leg thereof extending through an end portion of the plug and into said chamber in said plug, and with the graduated leg thereof extending through said end portion of the plug and into said groove, the bend of the thermometer extending outwardly of said end portion of the plug, and said end portion of the plug having an extension with a recess therein, and said bend being located within said recess where contact with the bend by the float is prevented.

11. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, there being a chamber provided in said plug and being in communication with said passage in said plug, and a thermometer carried by said plug and having its bulb located in said chamber in said plug.

12. In a tester of the type disclosed which comprises a jar with a suction tip at an end thereof and a suction bulb at the other end thereof, and a hydrometric float in the jar; a thermometric device comprising a plug fitting within the jar with a liquid seal contact and having a passage extending therethrough for establishing communication between the chambers provided in the jar at both sides of the plug, a chamber provided in said plug and having separate means of communication respectively with said passage and a chamber of the jar, and a thermometer carried by said plug and having its bulb located in said chamber in said plug.

13. In a tester of the type disclosed which com-

prises a jar with a suction tip at an end thereof, a suction means at the other end thereof, and a hydrometric float in the jar, a plug in the jar for providing jar chambers at both sides of the plug, and means for establishing communication between the chambers in the jar at both sides of the plug, said plug being provided with a thermometer bulb chamber having communication with said communication establishing means, and having separate means communicating with a 10 chamber of the jar, and a thermometer so mounted as to have its bulb located in said bulb chamber.

14. In a tester of the type disclosed which comprises a jar with a suction tip at an end thereof, a suction means at the other end thereof, and a hydrometric float therein; a plug in the jar for providing jar chambers at both sides of the plug and having a passage communicating with said jar chambers, said plug having therein a thermometer bulb chamber forming a part of said passage, and a thermometer so mounted as to have its bulb located in said bulb chamber.

EMIL A. STROMBERG.
